United States Patent Office

Des. 212,140
Patented Aug. 27, 1968

212,140

LUGGAGE CARRIER

Roger E. Hoffman, P.O. Box 473,
Castle Rock, Colo. 80104

Filed Mar. 24, 1967, Ser. No. 6,378

Term of patent 7 years

(Cl. D90—3)

FIG. 1

FIG. 2

FIG. 3

FIGURE 1 is a perspective view of the luggage carrier, illustrating my new design;

FIGURE 2 is a rear elevational view thereof; and

FIGURE 3 is a left side elevational view.

The motor bicycle shown fragmentarily in broken lines in FIGURE 3 is included for illustrative purposes only.

I claim:

The ornamental design for a luggage carrier, as shown and described.
